METHOD AND SYSTEM OF CONDITIONING
FIBERJohn Blewett, Dallas, Tex., assignor to The
Murray Company, Dallas, Tex.

Application December 21, 1943, Serial No. 515,094

8 Claims. (Cl. 19—66)

1

This invention relates to new and useful improvements in methods and systems of conditioning fiber and particularly seed-cotton.

For a number of years there has been a great demand for mechanical cotton gathering or harvesting apparatuses in order to reduce the expense and labor of gathering cotton crops, especially in large cotton-producing areas. Also it is essential to harvest cotton as soon as possible after it has opened so that it will not be exposed to rain and other inclement weather which often lowers the value of the lint from \$5.00 to \$10.00 a bale. A considerable investment of time and money has been made in the development of a satisfactory cotton harvesting machine with the result that an efficient machine is now on the market and in use. Due to the present scarcity of farm labor, the demand for mechanical cotton harvesters is greater than the supply.

Although the machine efficiently gathers the cotton, one machine with a single operator gathering approximately one bale per hour, an excessive quantity of green leaves as well as other extraneous matter is removed from the cotton plant along with the lint. At the present time, the cleaners or extractors which are in general use will not remove this green leaf from the seed-cotton, whereby the value of the mechanically-gathered cotton is decreased from \$10.00 to \$20.00 per bale due to the presence of green leaf therein.

Therefore, one object of the invention is to provide an improved method of efficiently conditioning and increasing the value of fibers, such as cotton which has been gathered mechanically and which contains an unusual quantity of green leaves as well as sticks, stems, hulls and other trash.

An important object of the invention is to provide an improved fiber conditioning method wherein the green leaf is reduced to a soft, flexible or pliable condition and is then conducted with the fiber to a cleaning step in which the fiber and leaf are passed between rotating elements and a discontinuous grate-type cleaning surface, said fiber and leaf being simultaneously subjected to an air current or suction, whereby the leaf will be separated from the fiber and partially drawn into the openings of the cleaning surface so as to be stripped from said surface through the discontinuities thereof and withdrawn from the cleaning step together with other extraneous matter and the air current or suction.

Another object of the invention is to provide an improved fiber conditioning method, of the character described, wherein the fiber is dried

2

to wilt the leaf to a soft, flexible or pliable condition and wherein the cleaning surface of the cleaning step is disposed beneath the rotating elements and coacts with a downwardly-directed suction or air blast to rapidly and efficiently separate and remove the leaves from the fiber so as to eliminate roping, twisting and machining of said fiber, such coaction being assisted by the wiping action of cleaning cylinders.

10 A particular object of the invention is to provide an improved method of conditioning fiber having green leaf admixed therewith wherein the fiber is dried to wilt the leaf to a soft, flexible or pliable condition, and wherein a considerable quantity of wilted green leaf is separated from said fiber immediately subsequent to the wilting thereof and preferably by or due to the means employed for such wilting.

15 A further object of the invention is to provide an improved fiber conditioning method, of the character described, wherein the leaves and other extraneous matter may be quickly removed from the fiber in a substantially whole condition, whereby breaking and powdering of said leaves and consequent intimate admixing of the same with said fiber is reduced to a minimum.

20 Still another object of the invention is to provide an improved fiber conditioning system having means for wilting the green leaf admixed with the fiber to a soft, flexible or limp condition together with cleaning means which includes a discontinuous grate-type cleaning surface, rotating cylinders disposed above and coacting with the cleaning surface and means for inducing a downwardly-directed air current past the cylinders and through said cleaning surface, whereby said leaf is separated from and forced through openings of the cleaning surface by the interdependent coaction of all of the elements.

25 30 35 40 45 50 55 A still further object of the invention is to provide an improved system of conditioning fiber having green leaf admixed therewith which includes a conditioner having an air current for drying the fiber and wilting the green leaf to a soft, flexible or pliable condition, the conditioner being rotated transversely to the air stream so as to gently tumble said fiber and having elongate openings formed in its exterior, whereby said air stream will have a tendency to pick up and separate the wilted leaf from the fiber and eject the same through the elongate openings, the ejection of said leaf being facilitated by its pliability which permits folding or bending thereof and prevents bridging of said openings.

Still another object of the invention is to pro-

vide an improved fiber conditioning system, of the character described, wherein a drier may be employed for wilting the green leaf to the desired condition and the air from the drier may be utilized as the source of the air current which is passed through the cleaner, and wherein substantially the entire area of said cleaner is subjected to the current of air so as to provide a continuous, uniform condition within the cleaner.

A construction designed to carry out the invention will be hereinafter described together with other features of the invention.

The invention will be more readily understood from a reading of the following specification and by reference to the accompanying drawings, 15 wherein an example of the invention is shown, and wherein:

Figure 1 is a plan view of a fiber conditioning system, constructed in accordance with the invention for carrying out the improved method 20 and system.

Figure 2 is a longitudinal, vertical, sectional view of the conditioner or drier.

Figure 3 is an enlarged, transverse, vertical, 25 sectional view of the conditioner.

Figure 4 is an enlarged, plan view of a portion of the grate-type screen which extends circumferentially of the conditioner reel or drum,

Figure 5 is a longitudinal, vertical, sectional view of one of the cleaners, showing the temporary air-fiber separation and the conveyor-distributor for conducting the fiber to the cleaners,

Figure 6 is a reduced side elevation of one of the other cleaners, and

Figure 7 is an enlarged, isometric view of a portion of the discontinuous grate-type cleaning surface.

In the drawings, the numeral 10 designates a cotton gin which is arranged in more or less conventional manner and which includes a conditioner drier 11, a plurality of cleaners 12, 13 and 14, and a battery of gin stands 15. A suction duct 16 extends from the exterior of the gin to the conditioner 11 to convey the mechanically-gathered seed-cotton to said conditioner. As is clearly shown in Figure 2, a separator 17 is interposed and establishes communication between the conditioner and duct 16. The separator is substantially identical to the separator shown in the United States Letters Patent to Bronson C. Woodford, No. 2,114,553, issued April 19, 1938, and No. 2,141,585, issued December 27, 1938. A suction conduit 18 is connected in the lower end of the rear wall of the separator and communicates with the interior thereof through a vertically-curved, longitudinal sheet or partition 19 which has a foraminous or perforated upper portion to accommodate the passage of air and prevent the cotton from being drawn into the conduit 18. For drawing an unobstructed stream of air through the duct 16, separator 17 and conduit 18, a suction fan (not shown) communicates with the far or opposite end of said conduit. An open, rotatable wiping reel 20 extends transversely within the interior of the separator for wiping the perforated portion of the partition 19 so that the passage of air is not interfered with and the cotton is directed to the lower end of said separator. For sealing the lower end of the separator and for directing the cotton to the conditioner 11, a vacuum paddle wheel 21 is disposed below the wiping reel 20.

Although the conditioner or drier may be of the conventional type, it is preferably of the "big reel" type and is very similar to the conditioner

shown in the United States Letters patent, No. 2,160,253, issued to Parrish H. Rylander on May 30, 1939. One end of the conditioner is provided with an inlet chamber 22 for receiving the cotton from the vacuum wheel 21. A continuous screw-type reel or drum 23 having open ends, is disposed longitudinally within the interior of the drier upon an axial, rotatable shaft 24 and has one end portion positioned within the chamber 22.

As is clearly shown in Figure 3, a plurality of radial arms 25 have their inner ends secured to the shaft 24 and extend outwardly from said shaft for supporting a continuous, spiral baffle 26 which surrounds the shaft (Fig. 2). The baffle extends from the end of the shaft within the inlet chamber 22 throughout the length of said shaft and terminates short of the far or outlet end wall of the conditioner so as to provide a vertical space or passage 22a at such end. It is noted that the inner peripheral edge portion of the baffle 26 is spaced from the shaft 24 whereby an annular passage or opening 27 is provided around said shaft throughout the entire length of said baffle. By reducing the diameter of the initial flight of the baffle within the inlet chamber 22, the bottom or floor of said chamber may be disposed above the lowermost point of the drum 23 and said baffle. A longitudinal angle bar 28 is secured to the extreme outer end of each radial arm 25 and extends throughout the length of the drum. It is pointed out that the angle bars are secured to the radial arm in such manner that one leg of each angle bar projects inwardly toward the shaft 24 so as to form an inwardly extending lug. Although screen wire or other foraminous material may be secured to the outer marginal edge portions of the baffle 26 and the angle bars 28 so as to surround and enclose said baffle and bars, it is preferable to employ a grate-type screen 29 having a plurality of elongate openings or foraminations 70 which extend circumferentially around the reel or drum 23. The screen 29 may be formed of any suitable material and includes annular, circumferential members or wires 71 and longitudinal members or wires 72 which extend throughout the length of the drum transversely of the circumferential members. As is clearly shown in Figure 4, the members 71 and 72 are suitably fastened to each other and may be interwoven, the distance between the members 72 being greater than the distance between said members 71 so as to provide the elongate, circumferential openings or foraminations 70.

As the cotton enters the inlet chamber 22 from the vacuum wheel 21, it manifestly will be engaged by the reduced first flight of the baffle 26 which is located within said chamber. Since there is no screen enclosing this reduced flight, the same acts as an ordinary screw conveyor to push the cotton from the inlet chamber into the interior of the screen drum 23. The latter is rotating in a counterclockwise direction (Fig. 3) and at a comparatively slow speed, whereby the cotton is retained in the lower portion of the drum and is not carried completely therearound. Due to the baffle rotating with the drum, said baffle does not act as an ordinary conveyor to push the cotton through said drum, but merely acts to slowly move the cotton forwardly or longitudinally therein. Since there is no forcing action, the cotton settles to the lower portion of the drum and rotation of said drum causes the lugs formed by the inwardly extending legs of the angle bars 28 to engage and tend

to spread said cotton over the inner surface of the screen 29 toward the right in Figure 3. In other words, the lugs lift the cotton upwardly on the inner surface of the drum.

For drying the cotton and wilting the green leaves, both of which are spread over the inner surface of the drum by the action of the lugs extending inwardly thereto, a plurality of elongate nozzles 73 are provided in one side wall of the conditioner or drier 11. As shown in Figure 3, these nozzles are disposed in horizontal alignment and may extend substantially throughout the entire length of the conditioner. It is noted that the nozzles may be continuous to provide one elongate continuous nozzle extending longitudinally of the conditioner and are disposed adjacent the lower portion of the drum 23 in a horizontal plane so as to be directed inwardly toward the medial portion of said conditioner. A manifold 74, which communicates with a hot air pipe or flue 75 (Fig. 1), is connected to the nozzles 73 for supplying hot, dry air under pressure to the interior of the conditioner through said nozzles. Due to the disposition or location of the nozzles 73, hot, dry air is directed into contact with the seed cotton at the time that said cotton has been spread in a comparatively thin layer on the drum interior. Therefore, the air contacts each lock of cotton and each green leaf so as to thoroughly dry the cotton and wilt the leaf. The air, which has a jetting action, also forces cotton, which is riding upwardly on the drum interior back toward the medial portion of the drum, whereby a gentle rolling or tumbling motion is imparted to the cotton within the lower portion of said drum. Wilting of the green leaf reduces the same to a soft, flexible or pliable condition and as said leaf moves upwardly opposite one of the nozzles 73, the jetting action of the air will pick up and carry the leaf across the interior of the drum 23. Due to the provision of the elongate openings 79 of the screen 29, a considerable portion of the wilted green leaf will be folded and forced through said openings by the air current or blast ejected from the nozzle. The leaf which does not pass through the opening will be spread with the cotton by the lugs formed by the angle bars 28 and again carried upwardly until the air blast or stream again contacts the same. Thus, it will be seen that a gentle rolling or tumbling motion is given to the cotton and leaf and that the same will be kept separated to a degree within the drum. The rotating spiral baffle constantly acts to move the cotton and leaf slowly along the inner surface of the drum toward the outlet end of the conditioner.

During the travel of the cotton and green leaf through the drum, the gentle tumbling motion imparted thereto by the location of the air nozzle and the action of the lugs will cause a considerable proportion of the wilted green leaf, as well as sticks, stems, dirt, dust and other extraneous matter, to pass through the openings 79 of the screen 29 and drop outwardly away from said drum so as to be separated from the cotton. This separated leaf and extraneous matter falls into a suitable longitudinal trough 76 having mounted therein a screw-conveyor 77 which leads to a discharge outlet 78 having a vacuum wheel 79 mounted therein. After contacting the cotton and green leaf, the air flows through the central passage 21 which is formed around the shaft 24 to the vertical space or passage 22a and escapes with the cotton and remaining green leaf through

a suitable blowout connection 80 which communicates with the cleaner 12 through a pipe or flue 30 and a suitable transition 31 (Figs. 1 and 5).

A separator 32, similar to the separator 17, is interposed and establishes communication between the cleaner and the transition 31 and includes a suction conduit 33, a transverse, vertically-curved partition 34 having a foraminous or perforated upper portion, a rotatable wiping reel 35 and a vacuum paddle wheel 36. As is clearly shown in Figure 5, the conduit 33 communicates with the upper end of the cleaner 12 through an amplified or flared hood 37 whereby the air separated from the cotton by the separator 32 is discharged into and spread substantially throughout the entire area of said cleaner. The dried seed-cotton is discharged through the vacuum wheel 36 into a conveyor-distributor 38 which extends longitudinally of the gin (Fig. 1) and communicates with the cleaners 13 and 14 as well as with the cleaner 12. A pair of parallel, oppositely-rotating screw conveyors 39 are mounted within the distributor 38 for spreading the cotton and conveying the same to the various cleaners. The end of the distributor opposite the separator 32 may communicate with a suitable overflow bin (not shown) from which the cotton may be returned by a suitable pipe 40 to the duct 16, whereby the excess seed-cotton may be again carried through the conditioner 11.

A feeder unit 41, having a pair of spaced, parallel feed rollers 42, is disposed above each cleaner so as to establish communication with the conveyor-distributor 38 and feed the cotton to the cleaners. The feeder unit 41 is disposed at one end of the cleaner and a plurality of spaced, horizontal cleaning cylinders or drums 43 are mounted transversely within said cleaner. The cylinders rotate in a counter-clockwise direction and are disposed over concave cleaning surfaces 44, each surface being swung on an arc concentric to the shaft of its respective cylinder. The bottom of a cleaning chamber 45 within which the cylinders are disposed is formed by the surfaces 44.

Each cleaning surface is of a discontinuous grate-type and includes a plurality of arcuate fingers 46 which are circular in cross-section and which are swung on an arc of a greater radius than the cylinders 43. As is clearly shown in Figure 7, the fingers 46 are arranged in spaced, parallel rows which extend transversely of or across the cleaning chamber 45 and each finger is preferably disposed in the same vertical plane as the contiguous fingers of the adjacent rows. Each transverse row of fingers is welded or otherwise secured to a sleeve 47 journaled upon an elongate, transverse bolt or rod 48. If desired, each sleeve 47 may be divided into several relatively short sections, although each bolt 48 extends entirely across the cleaning chamber 45. For vertically adjusting the position of the fingers 46, a short, flat arm 49 is mounted on each end of each sleeve so as to extend parallel to said fingers and has a slot 50 formed in the outer or free end thereof. A stud bolt or screw 51 extends through each slot 50 and engages within an opening formed in a vertical plate 52, a plurality of which preferably extend longitudinally beneath the chamber 45 for supporting the bolts and sleeves. The fingers 46 of each row are of such length and are so spaced as to barely clear the ends of the fingers of the adjacent row which are fastened to the adjacent sleeve 47 and their outer ends are preferably

bevelled as shown at 53. It is noted that the most desirable position of the fingers is as shown in Figure 7, wherein the end of each finger is spaced a slight distance above the inner end of the contiguous finger in the adjacent row, whereby a contracting throat or space 54 is provided therebetween for accommodating the passage of the green leaf as will be hereinafter more fully explained. Manifestly, this position of the fingers is attained by properly adjusting the stud bolts or screws 51. The cleaning surfaces 44 and fingers 46 are shown and described in greater detail in my co-pending application, Serial No. 515,095, filed December 21, 1943.

A conveyor-distributor 55 communicates with the end of the cleaning chamber 45 opposite the feeder unit 41 for discharging the cleaned seed-cotton from said chamber and a vacuum discharge wheel 56 is interposed between the distributor and the chamber to prevent the discharge of air with said seed-cotton. A suitable hopper 57 and flue 58 connect the bottom of the cleaning chamber to a trash conveyor (not shown) for removing the trash separated from the cotton in said chamber as well as the air which passes through the chamber, cotton and the cleaning surfaces 44.

As has been hereinbefore set forth and as is clearly shown in Figure 6, one of the feeder units 41 establishes communication between the conveyor-distributor 38 and the cleaning chamber of each cleaner 13 and 14. These cleaners are substantially identical to the cleaner 12 and, if desired, may be supplied with the relatively hot, dry air from the conditioner 11. However, it is preferable for the hood 37 of each cleaner 13 and 14 to communicate through a suitable transition 59 with an air inlet duct 60 which is supplied with air from another source, such as by fans (not shown). The conveyor-distributor 55, disposed beneath and communicating with the discharge end of the cleaning chamber of each cleaner, overlies the gin stands 15 for distributing and conducting the cleaned seed-cotton thereto (Fig. 1). An overflow bin 61 receives the excess cotton from the far end of the distributor 55 and is provided with a return suction pipe 62 for returning said cotton to the inlet end of said distributor. A separator 63, substantially identical to the separator 17, is preferably interposed between the pipe 62 and the distributor 55 so as to separate the cotton from the motivating air current. The latter is supplied by means of a suction duct 64 which is connected to the suction conduit 18. If desired, an elbow 65 and valve (not shown) may establish communication between the pipe 62 and inlet duct 16, whereby cotton may be fed directly to the gin stands without being carried through the drier 11 or any of the cleaners 12, 13 and 14.

In operation, the seed-cotton to be cleaned is drawn through the duct 16 and separator 17 into the conditioner or drier 11 wherein said seed-cotton is dried and a considerable quantity of the green leaf dirt and other fine trash is removed therefrom, as has been hereinbefore clearly set forth. Manifestly, the drying of the cotton will somewhat reduce the dryness of the air introduced into the conditioner by the manifold 14 and nozzles 13. However, another important action takes place in the conditioner and this is the wilting of the green leaf embedded or admixed with the seed-cotton to a soft, flexible or pliable condition prior to its introduction into the cleaners, whereby said leaf will remain sub-

stantially intact or in a relatively whole state. The seed-cotton, the wilted green leaf and the relatively hot, dry air are conveyed from the conditioner to the separator 32 by the blow-out connection 80, flue 30 and transition 31, the air being separated from the cotton and leaf and passing through the pipe 33 into the hood 37. Thus, the air is delivered to and passes through the chamber 45 of the cleaner 12 instead of being discarded in the usual manner, whereby said air may be utilized to assist in the removal of the leaf from the cotton.

As has been hereinbefore set forth, the seed-cotton and soft, flexible leaf enter the cleaner by way of the vacuum wheel 36, distributor 38 and feeder unit 41 and passes to the left of and beneath the left-hand cylinder 43, which is rotating in a counter-clockwise direction as are the other cylinders. This rotation of the cylinders will cause the cotton to travel longitudinally and toward the right of the chamber 45, over the concave cleaning surfaces 46 and beneath said cylinders. The motes, dirt and other fine extraneous matter or trash will fall through the longitudinal spaces between the fingers 46 which are spaced from and swung on an arc having a slightly greater radius than the cleaning cylinders. The green leaf, being larger than the spaces between the fingers, will ordinarily bridge said fingers so as to not pass through said spaces. However, due to the soft, flexible condition of the leaf, the air which passes vertically through the chamber 45 from the hood 37 to the hopper 57 will bend or fold said leaf upon itself and force the same through the longitudinal spaces. The leaf which bridges the fingers will adhere or cling to the fingers due to the air current, and will have portions thereof forced into the spaces between said fingers. Since the air is still relatively hot, it will tend to further increase the flexibility of the leaf. The wiping action of the cleaning cylinders 43 will move the bridging leaf longitudinally of the fingers from the ends of which said leaf will be shedded or stripped and drawn through the contracting throats 54. Of course, other large trash also will be forced through the throats 54 as well as the longitudinal spaces by the combined action of the downwardly-directed air current and the counter-clockwise rotation or wiping action of the cleaning cylinders 43. Thus, the seed-cotton will be thoroughly cleaned by the time it reaches the vacuum wheel 56 and is discharged into the conveyor-distributor 55 which conveys the same to the gin stands 15. The leaf and other extraneous matter which pass through the cleaning surfaces 44 drop into the hopper 57 and are directed by the flue 58 to a dirt or trash conveyor (not shown).

From the foregoing, it is manifest that mechanically-gathered seed-cotton is efficiently and thoroughly cleaned by the herein described improved method and system. Although it is preferable to utilize the air from the conditioner, said air could be obtained from any other source so long as it was relatively hot and dry. The co-action of the downward stream or current of air and the discontinuous, grate-type cleaning surface together with the wiping action of the cleaning cylinders are among the most important and essential features of the system and could not be eliminated without the substitution of an equivalent arrangement. However, the wilting of the green leaf to a soft, flexible or pliable condition is substantially of equal impor-

tance and essentialness and, of course, might be accomplished by means other than that described herein. The wilting of the leaf which permits the removal or separation thereof from the seed-cotton in a substantially intact or whole condition is not sufficient to entirely dehydrate said leaf and render the same brittle. In other words, this wilting facilitates and makes possible the removing or separating which takes place in the conditioner and cleaners, whereby breaking and powdering of the leaf and consequent admixing of the same with the seed-cotton is reduced to a minimum. In addition, the removal of a portion of leaf in the conditioner reduces the load and the cleaners and makes for a purer cotton. The efficiency of the method increases the efficiency of the cleaning step so as to decrease the time thereof, whereby the relative size of the cleaner or the number of the cleaning cylinders may be reduced and roping, twisting and machining of the cotton is substantially eliminated. Also, the necessity for the usual beating action of the cleaning cylinders is obviated as it is the wiping action thereof which is essential. All of these features are interdependent and coact to produce the new and improved results. Of course, hand-picked cotton may be cleaned by this method, although it is primarily designed for the conditioning of machine-gathered cotton.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A system for conditioning fiber containing green leaf including, a conditioner having a current of hot air therein for wilting the leaf to a limp condition, a cleaner having a chamber therein, the air current conducting the fiber and leaf from the conditioner to the cleaner, the chamber of said cleaner having a discontinuous grate-type cleaning surface, cleaning cylinders within said chamber rotating adjacent to and coacting with the cleaning surface, said fiber and leaf being fed to and carried by the cylinders between said surface and cylinders, and means for separating said air current from the fiber and leaf and directing the same downwardly within the chamber past the cylinders and through the surface, the air current urging and holding the leaf in engagement with said surface while being carried therewith by said cylinders and forcing said leaf in a substantially whole condition through the discontinuities of the surface so as to separate the same from the fiber.

2. A system as set forth in claim 1 wherein the conditioner includes, a foraminous cleaning surface, and means for utilizing the air current to eject a portion of the wilted leaf through the foraminous surface.

3. A fiber conditioning system as set forth in claim 1 wherein the discontinuous cleaning surface has a plurality of openings extending longitudinally of the direction of the rotation of the cylinders and movement of the fiber for permit-

ting the passage of the air current, whereby the combined action of said cylinders and current will force fine trash through the longitudinal openings, said surface also having transverse openings forming the discontinuities thereof for receiving and discharging the wilted leaf in a substantially whole condition.

4. A fiber conditioning system as set forth in claim 1 wherein the cleaning surface includes, a plurality of spaced elements arranged in spaced, parallel rows, the spaces between the elements receiving fine trash and the wilted leaf being discharged by the air current through the spaces between the rows.

5. A fiber conditioning system as set forth in claim 1 including, means for spreading the downwardly-directed air current throughout substantially the entire area of the cleaning chamber.

6. The method of treating gathered cotton mixtures containing seed cotton, trash and green leaves which includes, conveying and subjecting the mixture to a heated air current only sufficient to wilt the green leaves and render them soft and flexible, then progressively cleaning the cotton while moving the wilted green leaves therewith and extracting the trash and wilted green leaves from the mixture substantially without disintegrating said leaves, and carrying off the seed cotton.

7. The method of treating gathered cotton mixtures containing seed cotton, trash and green leaves which includes, subjecting the mixture to a heated air current only sufficient to wilt the green leaves and render them soft and flexible, separating the air current from the mixture, conducting the mixture to a cleaning area, and then cleaning the mixture and utilizing the separated air current to extract trash and wilted green leaves without disintegrating said leaves, whereby the seed cotton is cleaned.

8. A fiber-conditioning system for treating gathered cotton mixtures containing seed cotton, trash, and green leaves including, means for subjecting the mixture to a current of air, and screening the mixture, a cleaner, means for conducting the mixture from the screening means, means for separating the air current from the mixture and conducting the mixture to the cleaner, said cleaner having beaters and grates thereunder provided with transverse openings adapted to pass folded green leaves therethrough while trash is passing through the grates and means for directing the separated air current downwardly through the cleaning grates to carry the trash and leaves therethrough.

JOHN BLEWETT.
